[57] CLAIM

The ornamental design for a mini electric wire clamp, substantially as shown and described.

DESCRIPTION

FIG. 1 is a perspective view of a mini electric wire clamp in use, showing my new design;

FIG. 2 is an enlarged top view thereof;

FIG. 3 is an enlarged front view thereof;

FIG. 4 is an enlarged bottom view thereof;

FIG. 5 is an enlarged side view thereof;

FIG. 6 is a sectional view taken in the direction of the arrows on line 6—6 of FIG. 3;

FIG. 7 is a sectional view taken in the direction of the arrows on line 7—7 of FIG. 3; and

FIG. 8 is a perspective view thereof with the portion of an electric wire bundle in broken lines for illustrative purposes only.
